(57) **CLAIM**

The ornamental design for a barbecue grill with lights, as shown and described.

DESCRIPTION

FIG. 1 is an isometric view of a barbecue grill with lights showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof; and,

FIG. 7 is a rear elevational view thereof showing my design. No claim is made to the elements shown in broken lines, it is shown for illustration purposes only.

1 Claim, 6 Drawing Sheets
